CLAIM

The ornamental design for a milk frother as shown and described.

DESCRIPTION

FIG. 1 is a perspective view of a base unit of the milk frother design, shown without a cap for purposes of clarity.

FIG. 2 is a perspective view of the cap of the milk frother design, shown without the base unit for purposes of clarity.

FIG. 3 is another perspective view of the base unit of the milk frother design, shown without the cap for purposes of clarity.

FIG. 4 is another perspective view of the cap of the milk frother design, shown without the base unit for purposes of clarity.

FIG. 5 is a front view of the base unit of the milk frother design, shown without the cap for purposes of clarity.

FIG. 6 is a rear view thereof.

FIG. 7 is a left side view thereof.

FIG. 8 is a right-side view thereof.

FIG. 9 is a bottom view thereof.

FIG. 10 is a top view thereof.

FIG. 11 is a perspective view of the milk frother, shown with the cap on the base unit.

FIG. 12 is another perspective view thereof.

FIG. 13 is a front view thereof.

FIG. 14 is a rear view thereof.

FIG. 15 is a left-side view thereof.

FIG. 16 is a right-side view thereof.

FIG. 17 is a bottom view thereof; and,

FIG. 18 is a top view thereof.

The broken lines show portions of the article that form no part of the claimed design.

1 Claim, 10 Drawing Sheets
